UNITED STATES PATENT OFFICE.

LOUIS N. D. WILLIAMS, OF OGONTZ, PENNSYLVANIA.

UNITING ADJOINING PORTIONS OF KNITTED WEBS.

1,180,898.

Specification of Letters Patent.

Patented Apr. 25, 1916.

Application filed April 17, 1915. Serial No. 22,002.

To all whom it may concern:

Be it known that I, LOUIS N. D. WILLIAMS, a citizen of the United States, residing in Ogontz, Pennsylvania, have invented certain Improvements in Uniting Adjoining Portions of Knitted Webs, of which the following is a specification.

My invention consists of an improvement in the manufacture of that type of hosiery in which the leg and foot are composed of seamless tubular knitted web having a seamless toe pocket integrally knitted with the front end of the sole web of the foot, the stitches around the open end of this toe pocket and the stitches around the forward edge of the instep portion of the foot web being subsequently united by means of a separately produced chain of stitches.

My invention has for its object the cheapening of the production of hosiery of this type, an object which I attain by saving labor and preventing waste incident to the present method of producing such hosiery. Labor is saved by rendering unnecessary the application by hand to the "points" of a looping machine, stitch after stitch, first of the half course at the termination of the instep web of the stocking, and then of the half course around the open end of the toe pocket, or vice versa. Waste is prevented by eliminating the "handling web" now formed beyond the instep web and toe pocket for the purpose of facilitating the application to the looper points of the stitches which are to be united.

In the accompanying drawing Figure 1 is a sectional view of the forward end of the foot portion of a stocking web as now produced, with toe pocket upon the sole portion of the same, and a handling web beyond the toe pocket and instep web; Figs. 2, 3, 4, and 5 are sectional views illustrating, in connection with the needle cylinder, needles and web holders of an ordinary circular knitting machine, one means, in accordance with my invention, for transferring from the needles the stitches around the instep and toe webs of the stocking, and Fig. 6 is a sectional view of sufficient of a "looping machine" to illustrate the method of uniting these stitches.

An article of hosiery having a seamless tubular leg and foot, a seamless heel knitted integrally with the rear half of the leg and the sole portion of the foot, and a seamless toe pocket knitted integrally with the for-

ward end of the sole portion of the foot and having the stitches around the open mouth of the pocket united to those around the open end of the instep portion of the foot web may be regarded as a distinctively American type, and circular knitting machines adapted for either round-and-round knitting for the production of the seamless tubular leg and foot webs or for to-and-fro knitting with alternate narrowing and widening of the web for the production of the heel and toe pockets have been developed to such an extent as to be practically automatic in their action, hence, so far as the knitting of the stocking web is concerned, no further economies are to be expected.

The operation of uniting the stitches around the mouth of the toe pocket to those around the forward edge of the instep portion of the foot web is still, however, largely a hand operation and the work people employed in this branch of the industry not only receive relatively high wages but are not always available, for, even after, by careful training, they have acquired sufficient deftness to properly run the stitches onto the "points" of the looping machine, the work imposes such a strain upon the eyes as to render it undesirable, and it is difficult, if not impossible, for a modern hosiery mill to maintain a staff of "loopers" (as they are called) sufficient to keep up with the output of the knitting machines. A very serious item of expenses, moreover, in connection with this method of closing the toe of the stocking, is the necessity for forming a length of web beyond the looping courses around the toe pocket and instep web to constitute what is known as a "handling web," to facilitate the application to the points of the looping machine of the stitches which are to be united, this web, before beginning the looping operation, having to be raveled out and the yarn which formerly composed the handling web having no further value except as waste.

In Fig. 1 of the accompanying drawings, 1 shows part of the circular seamless foot web of a stocking, 2 the semi-circular course of stitches around the instep portion of said web, 3 the toe pocket knitted integrally with the sole portion of the web, 4 the semi-circular course of stitches around the mouth of said pocket which are to be united to the semi-circular course of stitches 2 in order to close the toe, and 5 the circular seamless

handling web which extends beyond the semi-circular courses of stitches 2 and 4.

In carrying out my invention I dispense with the objectionable hand operations heretofore necessary in closing the toe of the stocking, and hence with the necessity of forming the handling web 5, and transfer directly to a semi-circular set of looping points or quills (hereinafter, for convenience, termed "quills") first the stitches from the needles around one-half of the cylinder of the knitting machine and then the stitches from the needles around the other half of the same, the stitch-receiving quills, with the two courses of stitches upon them, being then applied to a looping machine whereby the stitches of one semi-circular course are united to those of the other semi-circular course in the ordinary way.

In Figs. 2, 3, 4 and 5 I have illustrated one form of device which may be employed for the purpose of transferring the stitches to and doubling them upon one and the same semi-circular set of stitch receiving quills, but it should be understood that my invention is not limited to this particular form of device, being, in this respect, independent of the particular means employed.

In Figs. 2, 3, 4 and 5, part of the needle cylinder of an ordinary circular knitting machine is represented at 6, the vertically reciprocating needles thereof at 7 and 7^a, and the horizontally reciprocating web holders at 8, all of which parts may be similar to those of machines now in common use unless the same may have to be modified to permit retraction of the web holders around the machine in order to release their hold upon the stitches on the needles. 9 represents a semi-circular ring segment having secured to and projecting therefrom a semi-circular set of stitch receiving quills 10, equal in number to the needles around one-half of the machine and so set as to accurately register with said needles.

Assuming that the knitting operation has been carried to the point of completion of the toe pocket, and that the needles 7 around one-half of the machine carry the stitches of the semi-circular course around the mouth of said toe pocket and the needles 7^a around the other half of the machine carry the semi-circular course of stitches at the end of the instep portion of the foot web, the ring segment 9 is first applied, as shown in Fig. 2, so that its quills 10 may be engaged with the stitches upon one set of needles, say the needles 7, said needles having previously been raised to such a point that the stitches upon them are below the open latches of the needles, or as it is technically termed "cleared." The needles are then fully retracted so as to cast their stitches onto the quills 10; and the web hold-ers co-operating with the needles 7 are re-

tracted so as to relieve these stitches of any further restraint.

The web holders around the other half of the machine having been retracted and the needles 7^a and the stitches thereon having been raised, the segment 9 is lifted, as shown in Fig. 3, until the quills 10, with the stitches upon them, can, without contacting with any part of the knitting machine, be swung downwardly and laterally until they register with the needles 7^a below the stitches thereon, as shown in Fig. 4. The segment 9 is then again raised so as to cause the quills 10 to engage the terminal stitches on the needles 7^a, as shown in Fig. 5, or said stitches are lowered on the needles so as to engage the quills and the needles 7^a are then retracted so as to cast the stitches therefrom onto the quills, which will then carry the two terminal courses of stitches 2 and 4. The ring segment and its stitch-carrying quills is then applied to the carrier 11 of an ordinary looping machine, as shown in Fig. 6, this carrier having a step-by-step movement, so that the stitches of each pair of the two semi-circular courses as well as the successive pairs of stitches can be joined in the ordinary way by means of the chain of stitches produced by said looping machine.

It will be evident, therefore, that my invention not only eliminates the application of the stitches by hand to the points of the looping machine, as now required in closing the toes of stockings, but also saves the waste now arising from the necessity of forming the handling web 5 adjacent to the course of stitches which are to be united.

While I have shown my invention as applied to a circular knitting machine it can also be used in connection with a machine having straight needle beds disposed back to back, the stitches being transferred to a straight set of quills first from the needles of one needle bed and then from the needles of the other needle bed, and instead of engaging the terminal courses of stitches upon the needles, the stitch receiving quills may engage the stitches of a previous course, the terminal course being subsequently cast or otherwise freed from the needles.

I claim:

1. The mode herein described of doubling stitches in one part of a knitted web with stitches of another part of the same, said mode consisting in first engaging a series of stitch-receiving quills with stitches of one part of the web while the terminal stitches thereof are still upon the needles of the knitting machine, then freeing the said terminal stitches from said needles, then engaging said stitch carrying quills with stitches of another part of the web while the terminal stitches thereof are still upon the needles whereby one and the same set of

- quills will carry two sets of stitches, one set in one part and the other set in the other part of the web to be united, and then freeing said terminal stitches from said needles.
2. The mode herein described of uniting the stitches in one part of a knitted web with stitches in another part of the same, said mode consisting in first engaging a series of stitch-receiving quills with stitches of one part of the web while the terminal stitches thereof are still upon the needles of the knitting machine, then freeing said terminal stitches from said needles, then engaging said stitch carrying quills with stitches of another part of the web while the terminal stitches thereof are still upon the needles, then freeing said terminal stitches from said needles whereby one and the same set of quills will carry two sets of stitches.
- one set in one part and the other set in the other part of the web to be united, and then uniting the two courses of stitches upon the quills by means of a separately produced chain of stitches.
3. The mode herein described of doubling stitches in one part of a knitted web with stitches in another part of the same, said mode consisting in first engaging a series of stitch-receiving quills with terminal stitches of one part of the web while the same are still upon the needles of the knitting machine, then casting said terminal stitches from said needles onto said stitch carrying quills, then engaging the quills with the terminal stitches of another part of the web while said terminal stitches are still upon the needles, and then casting said terminal stitches from said needles onto the quills whereby one and the same set of quills will carry two sets of stitches, one set in one part and the other set in the other part of the web to be united.
4. The mode herein described of uniting stitches in one part of a knitted web with stitches in another part of the same, said mode consisting in first engaging a series of stitch-receiving quills with terminal stitches of one part of the web while said stitches are still upon the needles of a knitting machine, then casting said terminal stitches from said needles onto said stitch carrying quills, then engaging the quills with terminal stitches of another part of the web while the same are still upon the needles, then casting said terminal stitches from said needles onto the quills whereby one and the same set of quills will carry two sets of stitches, one set in one part and the other set in the other part of the web to be united, and then uniting the two courses of terminal stitches upon the quills by means of a separately produced chain of stitches.
5. The mode herein described of doubling stitches around one-half of a tubular knitted web with stitches around the other half of the same, said mode consisting in first engaging a semi-circular series of stitch-receiving quills with corresponding stitches around one-half of the web while the terminal stitches thereof are still upon the needles of the knitting machine, then freeing said terminal stitches from said needles, then engaging said stitch carrying quills with corresponding stitches around the other half of the web while the terminal stitches thereof are still upon the needles of that half of the knitting machine, and then freeing said terminal stitches from said needle whereby one and the same set of quills will carry two sets of stitches, one set in one part and the other set in the other part of the web to be united.
6. The mode herein described of uniting stitches around one-half of a tubular knitted web with stitches around the other half of the same, said mode consisting in first engaging a semi-circular series of stitch-receiving quills with corresponding stitches around one-half of the web while the terminal stitches thereof are still upon the needles of the knitting machine, then freeing said terminal stitches from said needles, then engaging said stitch carrying quills with corresponding stitches around the other half of the web while the terminal stitches thereof are still upon the needles of that half of the knitting machine, and then freeing said terminal stitches from said needle whereby one and the same set of quills will carry two sets of stitches, one set in one part and the other set in the other part of the web to be united.
7. The mode herein described of doubling stitches around one-half of a tubular knitted web with those around the other half of the same, said mode consisting in first engaging a semi-circular series of stitch-receiving quills with the terminal stitches carried by one-half of the needles of a circular knitting machine, then casting the stitches from said needles onto the quills, then engaging said stitch carrying quills with the terminal stitches upon the needles around the other half of the machine, and then casting the stitches from the latter needles onto the quills whereby one and the same set of quills will carry two sets of stitches, one set in one part and the other set in the other part of the web to be united.
8. The mode herein described of uniting stitches around one-half of a tubular knitted web with those around the other half of the same, said mode consisting in first engaging a semi-circular series of stitch-receiving quills with the terminal stitches carried by one-half of the needles of a circular knitting machine, then casting the stitches from said needles onto the quills, then engaging said stitch carrying quills with the terminal

stitches upon the needles around the other half of the machine, then casting the stitches from the latter needles onto the quills whereby one and the same set of quills will carry 5 two sets of stitches, one set in one part and the other set in the other part of the web to be united, and then uniting the two semi-circular courses of stitches upon the quills by means of a separately produced chain of 10 stitches.

9. The mode herein described of doubling stitches around one-half of a tubular knitted web with stitches around the other half of the same, said mode consisting in first engaging 15 a semi-circular series of stitch-receiving quills with corresponding stitches around one-half of the web while the terminal stitches thereof are still upon the needles of the knitting machine, then freeing said terminal stitches from said needles, then raising said stitch-receiving quills and the needles around the other half of the machine, with the stitches upon them, then swinging said stitch-carrying quills downwardly and laterally into register with the raised needles around the other half of the machine, then engaging said quills with corresponding stitches in that half of the web while the terminal stitches thereof are still 20 upon the needles of that half of the knitting machine, and then freeing said terminal stitches from said needles, whereby one and the same set of quills will carry two sets of stitches, one set in one part and the other set 25 in the other part of the web to be united.

10. The mode herein described of uniting stitches around one-half of a tubular knitted web with stitches around the other half of the same, said mode consisting in first engaging 30 a semi-circular series of stitch-receiving quills with corresponding stitches around one-half of the web while the terminal stitches thereof are still upon the needles of the knitting machine, then freeing said terminal stitches from said needles, then raising said stitch-receiving quills and the needles around the other half of the machine, with the stitches upon them, then swinging said stitch-carrying quills downwardly and laterally into register with the raised needles around the other half of the machine, then engaging said quills with corresponding stitches in that half of the web while the terminal stitches thereof are still 35 upon the needles of that half of the knitting machine, and then freeing said terminal stitches from said needles whereby one and 40

the same set of quills will carry two sets of stitches, one set in one part and the other set in the other part of the web to be united, 60 and then uniting the semi-circular courses of stitches upon the quills by means of a separately produced chain of stitches.

11. The mode herein described of doubling stitches around one-half of a tubular knitted web with those around the other half of the same, said mode consisting in first engaging 65 a semi-circular series of stitch-receiving quills with the terminal stitches carried by one-half of the needles of a circular knitting machine, then casting the stitches from said needles onto the quills, then raising said quills and the needles around the other half of the machine, with the stitches upon them, then swinging said stitch-carrying quills 70 downwardly and laterally into register with said raised needles, then engaging said quills with the terminal stitches upon said needles, and then casting said terminal stitches from said needles, whereby one and the same set of 75 quills will carry two sets of stitches, one set in one part and the other set in the other part of the web to be united.

12. The mode herein described of uniting 80 stitches around one-half of a tubular knitted web with those around the other half of the same, said mode consisting in first engaging a semi-circular series of stitch-receiving quills with the terminal stitches carried by one-half of the needles of a circular knitting 85 machine, then casting the stitches from said needles onto the quills, then raising said quills and the needles around the other half of the machine, with the stitches upon them, then swinging said stitch-carrying quills 90 downwardly and laterally into register with said raised needles, then engaging said quills with the terminal stitches upon said needles, and then casting said terminal stitches from said needles, whereby one and the same set of quills 95 will carry two sets of stitches, one set in one part and the other set in the other part of the web to be united, and then uniting the two semi-circular courses of stitches upon the 100 quills by means of a separately produced 105 chain of stitches.

In testimony whereof, I have signed my name to this specification, in the presence of two subscribing witnesses.

LOUIS N. D. WILLIAMS.
